United States Patent

Des. 235,122
Patented May 20, 1975

235,122

FOOD STORAGE CONTAINER

Joseph R. Neri, Brooklyn, N.Y., assignor to Dart
Industries Inc., Los Angeles, Calif.

Filed Aug. 16, 1973, Ser. No. 388,874

Term of patent 14 years

Int. Cl. D7—01

U.S. Cl. D7—23

FIG. 1.

FIG. 2.

FIG. 3.

FIG. 4.

FIG. 1 is a top plan view of a food storage container showing my new design;

FIG. 2 is a side elevational view thereof;

FIG. 3 is a bottom plan view thereof; and

FIG. 4 is a cross-sectional view thereof taken along line 4—4 of FIG. 2.

I claim:

The ornamental design for a food storage container, substantially as shown.
